UNITED STATES PATENT OFFICE.

JOHN VICKERY, OF NEW YORK, N. Y.

DEVICE FOR FACILITATING THE TURNING OF PAGES.

SPECIFICATION forming part of Letters Patent No. 772,194, dated October 11, 1904.

Application filed January 4, 1904. Serial No. 187,617. (No model.)

To all whom it may concern:

Be it known that I, JOHN VICKERY, a citizen of the United States, and a resident of the city of New York, county of Queens, and State of New York, have invented certain new and useful Improvements in Devices for Facilitating the Turning of Pages, of which the following is a specification, reference being had to the accompanying drawings, in which—

10 Figure 1 is an elevation; Fig. 2, a detail in section, taken on the line xx of Fig. 1, seen in the direction of the arrow. Fig. 3 is another detail, also in section on the line yy of Fig. 1, seen in the direction of the arrow.

15 My invention is particularly applicable to facilitating the turning of pages of sheet-music, though it might also be otherwise employed, and I have accordingly shown it in the drawings as combined with an ordinary 20 well-known music-stand adapted to support before a musician printed sheet-music in a position properly displayed for reading.

25 A represents the desk or supporting-board of a music-stand, the usual support of which is indicated in part by A', extending to the floor, where it is supported by a foot in the usual way, or the desk A may rest directly upon the ordinary desk of a piano, for instance.

30 B is an upper holding device, consisting in this instance of a fixed staple B, fixedly secured to A in any convenient manner.

35 C is a lower holding device, likewise secured to A, but adapted to be opened or closed as required, said lower holding device consisting in this instance of bolts $m'm'$, connected by a movable bar m^2 , hinged at one end to one of said bolts, m' , and securable to the other bolt, m , by a thumb-screw m^3 passing through m^2 and engaging in a correspondingly-threaded recess in m ; but it will be understood that any other convenient means might be employed for imparting to the lower holding device capacity for opening when required and being secured in place when closed in normal position, as shown in Fig. 3. It will also be observed that the bar m^2 is preferably so shaped, as shown in Fig. 3, as to present on its inner side a plurality of circular openings, whereby the rods hereinafter

described are more effectually separated from each other.

$a a' a''$ are rods (composed, preferably, of wire) movably secured to B, as by eyes $d d' d''$, respectively, through which B passes loosely. The rods $a a' a''$ are thus prevented at all times from being separated from A, but in such a way as to insure capacity for extended movement in a multitude of directions relatively to the latter. $a a' a''$ are further restricted as regards their capacity for movement relatively to A by passing loosely between the latter and the lower holding device C when latter is normally closed, as shown in Fig. 3. To each rod—a, for instance—are rigidly secured a plurality (two as shown) of fingers $b c$, angularly disposed thereto and in the same plane with each other. To each rod, respectively, is also rigidly secured a manipulating-lever $g g' g''$, likewise angularly secured relatively to said rod and in the same plane substantially as the aforesaid fingers of the rod in question. The construction described admits of rotary movement by each rod approximately around its central longitudinal axis through an arc of approximately one hundred and eighty degrees, also some transverse movement by each rod relatively to stand A and neighboring rods, and also, when holding device C is opened, of movement by each rod in planes angularly disposed relatively to that of the surface of the stand A.

The operation of the device is as follows: To insert and hold the sheets of music, holding device C is opened and the rods raised or partially rotated around staple B until the face of the desk is cleared of the rods. The sheet-music is then laid upon the desk in the usual way, so as to be supported thereby. The leaves are now successively separated and a rod brought down to normal position (shown in Fig. 1) between each pair of leaves. After all the rods are thus placed between the leaves or pages of the music the holder C is closed and fastened. A pair of fingers $c b$ is thus placed between adjacent leaves. When it is desired to turn a leaf, the musician applies a finger to the appropriate lever— g , for instance—and pushes it through

the arc described. Such lever acting on the rod rotates and moves the latter, which correspondingly actuates the fingers c^2 b^2 to bear upon the leaf and turn it over.

- 5 It will be understood that the various fastenings described might be indefinitely varied in details of construction without departing from my invention, also that the number of rods employed may be indefinitely multiplied.
- 10 It will also be observed that by means of my devices the pages of music or other printed matter may be readily separated and turned without being actually handled by the operator, and this by a single and invariably certain movement of the finger, which is a great convenience, particularly to musicians, whose hands should be as little interfered with as possible in the manipulation of their instruments and to whom the turning of pages when required proves often an obstacle to successful performance of the music, owing to the

distance which the hand is required to travel and the tendency of the sheets to adhere undesirably to each other.

Having described my invention, what I claim as new, and desire to secure by Letters Patent, is the following, viz:

A device for turning a plurality of superimposed sheets, comprising a member to support said sheets, a plurality of rods provided with fingers disposed between and in contact with the sheets and with manipulating-levers free of the sheets, and a device permanently loosely and movably connecting said rods with said supporting member, and another normally closed openable device loosely movably and removably connecting said rods with said supporting member.

JOHN VICKERY.
